UNITED STATES PATENT OFFICE.

JOHN KIEWICZ, OF HYDE PARK, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE.

1,188,944.

Specification of Letters Patent. Patented June 27, 1916.

Application filed December 24, 1914. Serial No. 878,848.

To all whom it may concern:

Be it known that I, JOHN KIEWICZ, a citizen of the United States, residing at Hyde Park, in the county of Suffolk and State of Massachusetts, have invented certain new and useful Improvements in Sewing-Machines, of which the following is a specification, reference being had therein to the accompanying drawings.

10 This invention relates to sewing machines, and more particularly to method and construction whereby the handling of thread ends is improved.

15 More particularly the invention relates to sewing machines such as button hole sewing machines, wherein a succession of comparatively short stitching operations are effected and in which the loose thread at the beginning and end of each seam is desired to be 20 eliminated.

25 Among the objects of the present invention are to generally improve the operation of sewing machines with respect to the manipulation of the thread ends, to increase the convenience of operation and to effect a saving of thread.

30 Other objects will appear in the herein-after following description of an example or illustration in which the present invention is embodied.

35 To the attainment of the objects referred to the present invention consists in the novel parts, devices, combinations and other features described or disclosed in the accompanying description and drawings.

In the drawings, showing one embodiment of the present improvements, Figure 1 is a right hand elevation of a sufficient portion of a buttonhole stitching machine to show 40 the application of the present improvements, the various parts being shown in their initial or final position. Fig. 2 is a plan view of the work clamp plate and the parts carried by it, the same having its right hand edge 45 toward the observer and the parts being shown in the position taken by them during the stitching when the loose thread end is about to be cut off. Fig. 3 is a right elevation showing the same parts as in Fig. 2 and 50 in the same position. Fig. 4 is a section taken on the plane 4—4 of Fig. 2. Fig. 5 is a front elevation showing the same parts as in Figs. 2 and 3 and in the same position. Fig. 6 is a partial bottom plan view of the 55 machine, with its left hand side toward the

observer. Fig. 7 is a partial front elevation partly in section, taken on the plane 7—7 of Figs. 1 or 6. Fig. 8 is a perspective view of the cam controlling the mechanism more particularly constituting the present invention. Fig. 9 is a partial plan view on enlarged scale showing the relation of the thread hook or holder, the grip plate and the cutter.

Many of the general machine parts are of well known type and need not be specifically described. In the present drawings the same are, for convenience, generally modeled as in my prior pending application, Serial No. 827,276. I will now refer in a general way to some of the usual buttonhole machine parts. The present invention being applied particularly to the manipulation of the upper thread, the under stitching mechanism and the under thread are, for convenience, omitted from the illustrations. The upper thread is indicated by the reference α and the work by the reference γ . The machine comprises a bed plate 10 which may be attached to a suitable base. The bed plate 10 carries beneath it the cam casing 11 containing the main cam 12 indicated in dotted lines, this being mounted on a short vertical shaft and serving to operate or control many of the active parts of the machine, such as the cutter which cuts the buttonhole and the work clamp moving connections.

Above the bed plate 10 is the overhanging sewing machine arm 13. Mounted in the bed plate so as to be horizontally movable therein is the clamp plate 14. It may slide forward and backward for the regular feed purposes in stitching up and down the sides of the buttonhole and may swing laterally to assist the operation of stitching the two ends. The clamp plate 14 or its roughened portion 15 constitutes the lower of the two opposed work clamp members, the upper member or clamp 16 being, in the present illustration, capable of vertical opening and closing movements. For this purpose the upper clamp 16 is carried at the forward end of a clamp carrying arm 17 by which arm also the clamp is actuated. In the usual manner the clamp may be automatically closed upon the work before the cutting of the buttonhole and may be there locked and held during the movements of the clamp while the stitching proceeds, the clamp finally being opened at the completion of all of the operations so as to permit the work

being removed or shifted between the stitching of successive buttonholes. The eye-pointed vertically reciprocating upper needle 18 is carried at the lower end of a needle bar 19 slidably mounted in the overhanging arm 13. The upper needle will be reciprocated from the usual stitching shaft and will be operated in harmony with the under stitching mechanism. The upper needle 18

10 may be eccentric to its carrier and the entire stitching mechanism above and below the bed plate may be oscillated or rotated during the stitching of the ends of the buttonhole so as to carry the over-edge stitches around the ends in a curved path. The upper thread α may be controlled in an ordinary manner and it is shown, after passing from the usual tension and take-up, engaging with a certain thread controlling or

15 measuring or releasing member 20 which is automatically shifted; from whence the thread passes into the upper hollow end of the needle bar 19 and to a light tension device 21 carried at the lower end of the needle bar and thence to the needle 18. The drawings show a projection 22 engaging with and serving to effect the forward and backward shifting movements of the clamp plate 14, the part 22 being actuated from the main

20 cam 12.

Referring now more particularly to the new mechanisms involved in the present improvement, they comprise generally a thread holding and cutting means preferably involving a separate thread holding or gripping device 25 and a thread cutting device or knife 37, which parts may coöperate with a third member or plate 32 to assist their functions. These three parts and their fittings will be later described in detail. I will first explain in a general way the preferred functions and mode of operation of the parts.

The operation of a buttonhole stitching machine having the thread holding and cutting means hereof, may, for convenience, be substantially as follows: The operator, upon pressing the starting lever, puts the main cam into operation and immediately the work clamp is closed upon the work and then a buttonhole slit is cut in the work held in the clamp. The clamp now stands in cutting position. It thereupon is moved quickly forward to stitching position and preferably during such forward movement the slit will be stretched open by the automatic swinging apart of the two roughened under clamp members 15 in a well known manner. When the clamp has been shifted forward to stitching position the stitching shaft is thrown into action by its clutch and stitching commences. During this time the thread cutter 37 stands in retracted or inoperative position while the thread holder 25 is in its

50 thread gripping position holding the end

of the upper thread at a slight distance above and from the point on the work where the stitching is to commence. The stitching proceeds while the holder thus holds the thread-end. After the first few stitches the thread cutter moves inward from its retracted position to engage and cut close to the work the thread end held by the holder. This leaves a loose end of thread held by the holder. The cutter then retracts again to 75 inoperative position. The holder next moves from its thread gripping position outwardly to where it may discharge the loose thread end in a position removed from the stitching point, and the holder may then give a little quick discharging movement to throw out the thread. Thereupon the thread holder returns from its discharge position to its gripping position. In the meanwhile stitching has been proceeding and has continued 85 until the buttonhole is completed, upon which the stitching mechanism is brought to a stop with the upper needle out of the work. Immediately after the completion of the last stitch the thread holder shifts inwardly from its thread gripping position to 90 thread taking position, it reaching around and engaging the thread close to the work. The thread holder then returns with a portion of the thread to its thread gripping position, the thread manipulating device 20 at the top of the machine at this time allowing sufficient slack so that the thread holder may draw the thread laterally, as described. The thread holder then effects the gripping 100 of the thread, for example, by coöperation with the member or plate 32 and when so gripped the thread is held slightly stretched owing to the tension device 21 on the needle bar. At this point in the operations the 105 thread cutter again shifts from its retracted position inwardly to engage and cut the thread close to the work, thus leaving the end of the needle thread held by the thread holder. These operations are performed instantaneously and as soon as completed the work clamp in the natural operations of the machine, shifts rearwardly from shifting to cutting position, and, during such stitching, opens to release the work. During this final 115 period also the thread cutter will retract although its retraction need not be complete as it may continue at the commencement of the operation on the succeeding buttonhole. Finally the entire machine comes to a stop 120 with the parts in initial position. It will thus be seen that during the production of every buttonhole the thread holder operates once while the thread cutter operates twice, and in such a way that the thread end is cut close to the work, not only at the beginning but at the completion of each buttonhole, the very slight amount of loose thread that must be allowed for 125 between buttonholes being thus left in the 130

thread holder which, at the proper time, suitably discharges it.

Having indicated the preferred operation of the machine when constructed in accordance with the annexed illustrative drawings, I will describe in detail the structure and connections of the thread holder and cutter.

The thread holder or device 25 is in the form of a hook which facilitates its function of moving inward to the sewing point to reach around and engage the thread so as to pull the thread outwardly to where the holder may grip the thread by coöperation with the fixed plate or grip member 32. The 10 thread cutter 37 may be in any suitable form whereby it may be moved inwardly to the stitching point to cut the thread close to the work. We thus have the three coöperating members, the thread holding hook 25, the 15 thread cutting knife 37 and the grip plate 32 coöperating with the thread holder. These three coöperative members might be mounted in various modes so that they will occupy their proper operating positions during the 20 manufacture of buttonholes. Preferably these members are located adjacent to and to one side of, for example to the right hand side of, the stitching point. For convenience for example, they may all be carried by the 25 carrying arm 17 of the right hand upper clamp member 16. By this arrangement the parts are properly located, yet in such a way as not to interfere with the stitching or clamp operations and, indeed, upon the 30 opening of the clamp the members 25, 32 and 37 lift with the clamp, thus leaving the operator free to shift, insert or remove the work.

The details of the fittings of the thread 35 holding hook 25 may be varied indefinitely. It is shown as carried or formed at the extremity of a carrying arm 26, which is movable with respect to the clamp arm 17, having a pivot or screw 27 between the carrying 40 arms 26 and 17, and the arm 26 having an operating extension 28, preferably located at the rear where it may coöperate with the cam actuated parts that control the thread holder. The thread holder, its carrying 45 arm, and its operating extension are capable of oscillating from right to left between three positions. The normal or middle or thread gripping position is shown in full lines, Fig. 2, while the inward or thread engaging position and the outward or thread 50 discharging position are shown in dotted lines. The thread holder carrying arm 26 and the operating extension 28 may be made non-integral as shown. Thus the former 55 is capable of sliding in the latter, which permits adjustment of the precise position of the hook 25, the adjustment being made permanent by the set screw 29.

The swinging movement of the thread 60 holder being substantially horizontal its

pivot screw 27 is shown vertical. The carrier 26, or, rather, the extension 28 to which it is secured, is provided with a plate-like lug 30 provided with an aperture surrounding the screw 27. A certain friction device 70 shown in detail in cross section in Fig. 4 is interposed between the lug 30 and the pivot screw 27 for imposing a friction upon the shifting movements of the thread holder so that it will tend to steadily hold any position into which it is adjusted. This friction device comprises a leather or similar wash 75 31 between the lug or plate 30 and the head of the screw 27.

Referring next to the relatively stationary member 32, with which the thread holder 80 25 coöperates to grip the thread, this is seen to be a horizontal, flat, plate-like member carried in the proper position at the forward end of its carrying arm 33 which, at its 85 rear end, is rigidly secured to the clamp arm 17 by means of a screw 34 and the pivot screw 27 already referred to.

The thread cutter 37, like the thread holder and the grip plate, is carried at the 90 forward end of an arm 38. The arm 38, like the thread holder arm, is capable of swinging and for this purpose is pivoted on a screw 39 at the upper side of the clamp arm 17. The cutter arm 38 is provided with 95 an operating extension 40 extending rearwardly, adjacent to the operating extension 28 of the holder arm. As constructed the knife arm swings horizontally between two positions so that the knife may assume 100 its inward or cutting position and its outward or retracted position. A spring 41 is employed exerting a constant tendency to swing the extension 40 of the cutter arm to the left, that is from the observer, in Fig. 2, 105 so as to move the knife or cutter to retracted position. The normal or retracted position is determined by a stop pin 42 engaged by the extension 40. Fig. 2 shows in full lines the retracted or normal position of the 110 arm 40 and in dotted lines the position it will assume when the cutter is shifted inward to cutting position.

The elements 25 to 42 thus far described, as comprised in the present improvement, 115 are all shown carried upon the clamp arm 17 which, in turn, is carried upon the sliding clamp plate 14. It is highly desirable that a clamp plate be easily detachable and the present invention is so embodied in the 120 illustrated machine as to permit the detachment of the clamp plate without the need of effecting any detachments or adjustments of the thread holding and cutting device. On sliding forwardly out of place the clamp 125 plate 14 and all of the elements 25 to 42 described, withdraw along with the clamp plate. The operating extensions 28 and 40, by which all of the holder and cutter movements are effected, extend longitudinally. 130

that is, forwardly and backwardly, or substantially parallel to the sliding movement of extracting the clamp plate. By this construction whenever the parts are in position the operating extensions 28 and 40 are located to coöperate with the two upwardly extending actuating levers 50 and 51, seen in Figs. 2, 3 and 5. The lever 50, which is slotted at its upper end, engages the rear end of the extension 28 and is capable of shifting the same and, therefore, the thread holder, between its three positions. The actuating lever 51 is not shown slotted as it is required only to shift the extension 40 between two positions, opposed by the spring 41.

Having now described all of the parts seen in Figs. 2, 3, 4 and 5, including the thread holder and the thread cutter and the parts between them and their actuating levers 50 and 51 respectively, I will refer more particularly to the automatic or cam mechanism by which the actuating levers are caused to operate the thread holder and cutter in accordance with the operation previously set forth.

The main cam 12 already referred to, or the vertical shaft or sleeve carrying it, may have a downward extension in the form of a sleeve 52 and, for convenience, the cam 53, which controls the thread holder and thread cutter of the present invention, may be secured directly on the sleeve 52, as shown. The connections between the cam 53 and the operating extensions 28 and 40 of the holder and cutter arms are shown in Figs. 1, 6 and 7, and the cam 53, detached and in perspective, is shown in Fig. 8. Since, in the present embodiment of this invention the movements of the holder and cutter are not simultaneous, the cam 53 may have two separate actuating or cam surfaces, one for the thread holder and the other for the thread cutter.

The thread holder cam or surface 55 is shown as concentrically arranged at the under side of the cam or disk 53 and it is engaged by a follower 56 which rocks downwardly and upwardly according to the irregularities of the cam surface. The follower 56 is carried at the left extremity of a rock arm 57 fast upon a rock shaft 58 and the rock shaft 58 at the other end directly carries the upwardly extending actuating lever 50, before referred to, which engages the rear extension 28 of the thread holder carrying arm. Thus, any downward movement of the follower 56 caused by the cam surface 55 shifts the lever 50 and the extension 28 to the left while any upward movement shifts them to the right. A spring 59 is shown tending to hold the follower 56 against the cam 55. The cam or disk 53 likewise has a cam surface 61, with connections for controlling the

thread cutter 37. Thus, it is engaged by the follower 62 which is located at the end of rock arm 63 fast on rock shaft 64, the rock shaft also carrying the upwardly extending actuating lever 51, which operates against the force of the spring 41 to force to the left the operating extension 40 of the cutter carrying arm. A spring 65 tends to hold the follower 62 to the cam or surface 61.

The connections now having been described, reference will be made to the configuration or timing of the two cams 55 and 61 formed at the under side of the cam disk 53.

The cam 55, which operates the thread holder has one elevation for forcing the follower downward to shift the thread holder inward from its normal or central position and a depression for effecting the reverse movement to shift the holder from central to outward or discharging position. The cam 61 has two depressions, each for operating the cutter at a different point in the cycle of movements. The contour of the two cams and their coöperating action may be best described by referring to the different parts of the cam surface in consecutive order in connection with the successive functions of the two cams.

Normally when the machine is idle the follower of cam 55 stands at the point 55^a and the follower of cam 61 stands at the point 61^a (see Fig. 8.) In this condition of the parts the thread holder is in its middle or normal position while the thread cutter is substantially at its normal or outward position, having retracted from its cutting position. The holder is gripping the end of the thread passing through the eye of the upper needle.

After the machine is started and a slight revolution is effected of the main cam 12 and the cam disk 53, the follower of the cutter cam 61 arrives at the point 61^b and the knife is, therefore, entirely retracted; the follower of the holder cam 55 arriving at 55^b.

The operations of closing the clamp, cutting the button-hole slit, shifting the clamp forward from cutting to stitching position, starting the stitching and effecting the first few stitches, for example, seven or eight of them, are represented at Fig. 8 by the idle cam portions 61^b to 61^c and 55^b to 55^c, respectively.

The cutter cam portions 61^c and 61^d next come into effect to cause the thread cutter to move in and to cut the thread and to move out respectively. The holder cam portion 55^c next comes into effect to move the thread holder outward from its normal position to its most retracted position. A slight dip 55^d is shown in the cam which gives a little kicking movement to the thread holder assisting the discharge of the thread end and

at 55^s the holder again resumes normal position. In the meanwhile the thread cutter is idle through the corresponding positions 61^e, 61^t and 61^g. The stitching having proceeded and the buttonhole being completed, the holder cam portion 55^h comes into effect to shift the thread holder inward to engage the thread extending from the final stitch to the needle. The cam portion 55^t restores the thread holder to normal position at which it grips the thread against the grip plate 32. The thread is then somewhat under tension, as before explained. Next the cutter cam portion 61^t comes into effect to move the cutter inward so as to cut the thread close to the work, and, before the parts finally come to a stop, the cam shifts so that the follower is at the point 61^a, with the cutter moved outwardly, while at the same time, the holder cam portion 55^a has come around to its original position. It is during this final movement that the work clamp shifts back from stitching to cutting position and opens, whereupon the machine stops.

Aside from the details of the thread holding and cutting means or device, it will be seen that broadly the present invention embodies the combination with stitching means and feeding means for the work, of a suitable holding and cutting means adapted to operate in a certain manner, namely, to initially hold the thread end while the seam is started and to cut such thread end close to the work, thus leaving a short detached piece or fragment of thread held thereby, and to discard the thread fragment so produced by releasing or otherwise removing it, and after the stitching is done, or at the end of the seam, to re-engage and hold the thread at a point between the work and the needle, and to cut for the second time the held thread close to the work, thus at the completion of all operations leaving the thread end in a condition held by the holding and cutting means in readiness for the commencement of another seam.

It will thus be seen that I have described a sewing machine embodying the invention and attaining the objects and advantages hereinbefore recited, and other advantages will be apparent to those skilled in the art. Since many matters of design, arrangement, detail, structure, and other features may be variously modified or altered without departing from the novel principles involved, it is not intended to limit the present invention to such features excepting in so far as the same are set forth in the appended claims.

What I claim and desire to secure by Letters Patent is:

1. In a sewing machine, the combination of stitching and feeding means operable to form a series of successive seams, such as

spaced-apart buttonholes, operating means for actuating the stitching and feeding means in harmony, thread holding means adapted to take and hold the needle thread between the needle and work, thread trimming means adapted to sever the thread between the holding means and work, connections actuated or controlled from the operating means serving to automatically cause the holding means to take the thread after the completion of one seam and to hold it while the thread is severed between the holding means and work, and while a second seam is thereafter begun to be stitched and while the thread is thereafter a second time severed between the holding means and work, and connections actuated or controlled from the operating means serving to automatically cause the trimming means to twice sever the held thread, namely, both before and after the starting of the stitching of the second seam, so as to leave a thread fragment in the holding means.

2. In a sewing machine, the combination of stitching and feeding means, mechanism for operating the same to form a series of successive seams, such as spaced-apart buttonholes, thread holding means adapted to take and hold the needle thread between the needle and work, thread trimming means adapted to sever the thread between the holding means and work, operating means for operating the machine, and timing or controlling means actuated automatically from said operating mechanism to cause the holding means to take the thread and the trimming means thereafter to sever it in the period between the completing of one seam and the starting of the next seam, and to cause the trimming means thereafter and after the starting of the said next seam a second time to trim the held thread, leaving a thread fragment in the holding means.

3. In a sewing machine, the combination of stitching and feeding means, mechanism for operating the same to form a series of successive seams, such as spaced-apart buttonholes, a thread holder adapted to take and hold the needle thread between the needle and work, a thread trimmer adapted to sever the thread between the holder and work, and automatic means actuated from said operating mechanism constructed and timed to cause the holder to take the thread and the trimmer to sever it in the period between the completing of one seam and the starting of the next seam, and to cause the trimmer thereafter and after the starting of said next seam a second time, to sever the held thread, leaving a thread fragment in the holder.

4. In a sewing machine, the combination of a stitching means, a feeding means comprising a shiftable work-holding clamp, mechanism for operating said means to pro-

duce a series of successive seams, such as spaced apart buttonholes, a thread holder mounted on said clamp adapted to take and hold the needle thread between the needle and work, a thread trimmer mounted on said clamp and adapted to sever the thread between the holder and work, and automatic means actuated from said operating mechanism constructed and timed to operate 5 the holder and trimmer in harmony with the stitching means so that between the completing of one seam and the starting of the next the holder takes the thread and the trimmer thereupon severs it, and so that 10 thereafter and after the starting of said next seam the trimmer operates again to sever the held thread, leaving a thread fragment in the holder.

5. In a sewing machine, the combination of 20 stitching and feeding means, mechanism for operating the same to produce a series of successive seams, such as spaced apart buttonholes, a thread holder adapted to shift to and from the stitching point and fitted to 25 take and hold the needle thread between the needle and work, a thread trimmer adapted to shift to and from the stitching point and fitted to sever the thread between the holder and work, and automatic cam mechanism 30 means actuated from said operating mechanism constructed and timed to operate the holder and trimmer in harmony with the stitching means so that between the completing of one seam and the starting of the

next the holder takes the thread and the 35 trimmer thereupon severs it, and so that thereafter and after the starting of said next seam the trimmer operates again to sever the held thread, leaving a thread fragment in the holder. 40

6. In a sewing machine the combination of 45 stitching and feeding means and operating mechanism therefor, a thread trimmer adapted and fitted to sever the thread close to the work, automatic means actuated from 50 said operating mechanism constructed and timed to operate the trimmer in harmony with the stitching means so as to sever the thread twice for the formation of each seam, namely, after the starting and after 55 the completing of the seam, and means actuated from said operating mechanism for automatically taking the thread in the period between the completing of each seam and the subsequent thread-severing, and for holding the same, at a point between the needle and severing position, until after such thread-severing and after the starting of the next seam and after the subsequent thread-severing, and for disposing of the 60 resulting held thread fragment.

In testimony whereof, I have affixed my signature in presence of two witnesses.

JOHN KIEWICZ.

Witnesses:

J. WARREN NICHOLS,
Wm. C. BOISVERT.

duce a series of successive seams, such as spaced apart buttonholes, a thread holder mounted on said clamp adapted to take and hold the needle thread between the needle and work, a thread trimmer mounted on said clamp and adapted to sever the thread between the holder and work, and, automatic means actuated from said operating mechanism constructed and timed to operate the holder and trimmer in harmony with the stitching means so that between the completing of one seam and the starting of the next the holder takes the thread and the trimmer thereupon severs it, and so that thereafter and after the starting of said next seam the trimmer operates again to sever the held thread, leaving a thread fragment in the holder.

5. In a sewing machine, the combination of stitching and feeding means, mechanism for operating the same to produce a series of successive seams, such as spaced apart buttonholes, a thread holder adapted to shift to and from the stitching point and fitted to take and hold the needle thread between the needle and work, a thread trimmer adapted to shift to and from the stitching point and fitted to sever the thread between the holder and work, and automatic cam mechanism means actuated from said operating mechanism constructed and timed to operate the holder and trimmer in harmony with the stitching means so that between the completing of one seam and the starting of the

It is hereby certified that in Letters Patent No. 1,188,944, granted June 27, 1916, upon the application of John Kiewicz, of Hyde Park, Massachusetts, for an improvement in "Sewing-Machines," an error appears in the printed specification requiring correction as follows: Page 5, after line 47, insert the following paragraph:

Stated another way, it is novel with this invention to combine with the stitching, feeding and operating mechanisms of any sewing machine, a thread holder or holding means adapted and fitted to take the thread between the needle and work, a cutter or trimming means adapted and fitted to sever the thread between the holder and work, and automatic controlling means timed to cause the operation of the holder and trimmer so that after the completing of one seam or buttonhole and in the period between that time and the starting of the next seam, the holder takes the thread and thereupon the trimmer severs it, and so that thereafter and after the starting of the next seam, the trimmer for a second time severs the held thread, leaving a thread fragment in the holder. By this improvement the work may be shifted before the start of each seam without drawing thread. Also the needle thread end is left held in the holder suitably for the start of a seam. The thread is never lost control of and perfect trimming is insured. The loose held fragment is easily withdrawn and relinquished by the holder, where it can be disposed of without littering up the new seam. The very minimum of thread is wasted between seams, namely the small fragment left in the holder by the two cuttings;

and that the said Letters Patent should be read with this correction therein that the same may conform to the record of the case in the Patent Office.

Signed and sealed this 8th day of August, A. D., 1916.
